UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

LEVER MECHANISM FOR AIR-GUNS.

1,201,835.

Specification of Letters Patent. Patented Oct. 17, 1916.

Application filed March 31, 1916. Serial No. 87,945.

To all whom it may concern:

Be it known that I, CHARLES F. LEFEVER, a citizen of the United States of America, residing at Plymouth, in the county of Wayne 5 and State of Michigan, have invented certain new and useful Improvements in Lever Mechanism for Air-Guns, of which the following is a specification, reference being had therein to the accompanying drawings.

10 The invention relates to air guns of that type commonly known as pump guns in which the compression of the spring is effected by the sliding of a handle longitudinally of the barrel. This handle is connected with a lever mechanism for actuating the movable member that compresses the spring, and the present invention relates to an improvement in this operating mechanism.

In the drawings: Figure 1 is a sectional 20 elevation of the gun to which my improved mechanism is applied; the actuating handle being in retracted position; and Fig. 2 is a sectional elevation with the actuating handle in extended position.

25 As specifically shown, my improved lever mechanism is applied to a gun having a telescopic barrel in which the inward movement of the barrel effects the compression of the spring. The lever mechanism is, however, adapted for application to other types of 30 gun.

As shown, A is the rear barrel which is attached to the stock B, and C is the forward barrel telescopically engaging the barrel A. 35 D is the piston abutment in the barrel C, E the piston, F the shank and G the spring sleeved upon the shank, one end bearing against the piston and the opposite end against an abutment H in the barrel A, 40 which abutment passes through a longitudinal slot in the barrel C permitting the telescopic movement thereof.

I is a shoulder at the rear end of the shank F for engagement with the sear J which is 45 upon the trigger K, the arrangement being such that the rearward movement of the barrel C will carry with it the abutment D and piston E, compressing the spring G against the abutment H and carrying the shoulder I 50 into engagement with the sear J. My im-

proved lever mechanism is designed to accomplish this rearward movement of the barrel C and the compression of the spring by a relatively easy movement of the operating pump handle. To this end the levers 55 are so compounded that the power is increased in proportion to the increased resistance of the spring as it is compressed, rendering the final movement as easy as the initial movement. 60

In detail, L is the actuating handle, which is slidably mounted upon a guide M parallel to the barrel C.

N and O are two members of a break-joint lever which extends from the handle L to 65 the frame P at a point slightly in advance of the trigger. The two links N and O of this lever are respectively pivotally connected at Q and R to the handle L and frame P and are pivotally connected to each other 70 at S, the latter pivot being below the line connecting the pivots Q and R, so that the lever will break downward. Each of the links N and O is in the form of a channel bar, thereby constituting a housing for 75 concealing the coöperating mechanism. This coöperating mechanism comprises a lever T pivotally connected at U to the link O and having a sliding engagement at its inner end with a fulcrum pin V on the frame. The 80 outer end of the lever T is pivotally connected to a link W, the opposite end of which is attached to the telescopic barrel C, preferably to the bracket X which supports one 85 end of the guide M.

The arrangement and proportion of the parts just described is such that in the initial position of the operating handle L the members N and O and W and T lie in substantial parallelism. When the handle is drawn backward 90 and the swinging of the link O about the center R will carry the pivot U downward and rearward in relation to the stationary pivot V, which will swing the lever T drawing forward on the link W and carrying the barrel C backward. During the initial movement the leverage is least favorable for power, but the tension of the spring is slight and interposes comparatively little resistance. As 100

the movement progresses and the tension of the spring increases the leverage becomes more favorable for power through the combined effect of the more favorable angle of the link O and the elongation of the arm of the lever T between the pivot U and the stationary pivot V. The result is that the final movement which has the greatest resistance to overcome is performed as easily as the initial movement.

It will be observed that the members N and O constitute a hollow toggle and that the members W and T constitute a second toggle housed within the first and initially having its members arranged in substantial parallelism thereto. Further, the inner toggle formed by the members W and T has a changing leverage by the change in distance between the pivot U and a stationary pivot V, the lever T being slotted at T' to permit of such movement. Also the inner toggle has a greater angular movement but a lesser longitudinal movement at its connection with the barrel C than the movement of the handle L. It is due to these features of the construction that the change of leverage is obtained, which decreases the power required for the final compression of the spring.

What I claim as my invention is:—

1. In a gun, the combination with a member movable for the storage of power, of a longitudinally-movable actuating member, a break-down toggle lever operated by said actuating member, a second toggle lever having its movable end attached to said member for the storage of power, and a connection between the two toggles for actuating the second from the first with a progressive increase in power.

2. In a gun, the combination with a movable power-storage member, of a longitudinally-movable actuating member, a break-down toggle lever directly actuated by said actuating member, a second toggle lever having its movable end attached to the power-storage member, and a pivotal connection between one of the links of the first toggle and that of the second toggle for transmitting the movement of the one to the other.

3. In a gun, the combination with a member movable for power storage, of a longitudinally-movable actuating member, a toggle lever directly actuated from said actuating member having its links initially in substantial alinement, a second toggle lever having its links in substantial parallelism with the links of the first toggle lever and the movable end connected to said power-storage member, and a connection between the corresponding links of the two toggles for communicating movement from one to the other with an increase in power.

4. In a gun, the combination with a movable power-storage member, of a longitudi-

nal actuating member, a hollow toggle lever directly actuated thereby and having its links initially in substantial alinement, a second toggle concealed within the first toggle lever and having its movable end connected to said power-storage member, one of the links of said second toggle lever being pivotally connected to a link of the first lever and having a slidable connection with its stationary fulcrum for producing an increase in power.

5. In a gun, the combination with a barrel having an extension telescopically movable for the storage of power, an actuating member movable parallel to said barrel, a toggle lever directly connected to said actuating member and having its links initially in substantial alinement, a second toggle lever having its movable end connected to the telescopic extension of said barrel and a connection between said first and second toggle levers for communicating the movement of the former to the latter with an increase in power.

6. In a gun, the combination with a barrel having an extension telescopically movable for the storage of power, of an actuating member movable parallel to said barrel, a hollow toggle lever directly actuated by said member, and having its links initially in substantial alinement, a second toggle lever within the first having its links initially in substantial parallelism thereto and the movable end attached to said telescopic extension, and a pivotal connection between the links of said toggles imparting the movement of the first to the second on the increase in power.

7. In a gun, the combination with a barrel and an extension thereof telescopically movable for the storage of power, of an actuating member movable parallel to said barrel, a hollow toggle lever directly actuated thereby having its opposite end engaging a stationary pivot, a second toggle lever within the first having one end engaging a second stationary pivot and the opposite end connected to said telescopic barrel, a pivotal connection between the links of said first and second toggle which engage said stationary pivots, and means for permitting the increase in distance between the point of pivotal connection between said toggle levers and the engagement of said second toggle with its stationary pivot for producing a changing leverage of increasing power.

8. In a gun, the combination with a barrel of an extension barrel telescopically engaging said first barrel and movable for the storage of power, a guide connected to said telescopic extension extending parallel thereto, an actuating member slidable on said guide, a hollow toggle lever directly connected at one end to said actuating member and engaging a stationary pivot at its

opposite end, a second toggle lever within the first having one end pivotally attached to said guide and the opposite end slidably engaging a stationary pivot, and a pivotal connection between the corresponding links of said toggles.

Copies of this patent may be obtained for five cents each, by addressing the "Commissioner of Patents, Washington, D. C."

In testimony whereof I affix my signature in presence of two witnesses.

CHARLES F. LEFEVER.
